Primary Examiner — Mimosa De(74) Attorney, Agent, or Firm — Sanelimia & Associates, P.A.; Christian Sanelimia; Jesus Sanelimia(57) CLAIM

The ornamental design for a chair standing aid, as shown and described.

DESCRIPTION

FIG. 1 is an isometric view of a chair standing aid showing my new design;

FIG. 2 is a front elevational view thereof;

FIG. 3 is a top planar view thereof;

FIG. 4 is a bottom planar view thereof;

FIG. 5 is a right elevational view thereof;

FIG. 6 is a left side elevational view thereof; and,

FIG. 7 is a rear elevational view thereof showing my design. No claim is made to the chair shown in broken lines, it is shown for illustration purposes only.
